UNITED STATES PATENT OFFICE.

MELVILLE M. MOORE, SR., OF SANTA BARBARA, CALIFORNIA.

LIFTING-JACK.

SPECIFICATION forming part of Letters Patent No. 748,972, dated January 5, 1904.

Application filed August 7, 1903. Serial No. 168,595. (No model.)

To all whom it may concern:

Be it known that I, MELVILLE M. MOORE, Sr., a citizen of the United States, and a resident of Montecito Valley, Santa Barbara, in the county of Santa Barbara and State of California, have invented a new and Improved Lifting-Jack, of which the following is a full, clear, and exact description.

My invention relates to improvements in lifting-jacks, the same being especially adapted for use in raising the axles and wheels of vehicles; and the object that I have in view is the provision of a simple and durable construction by which an axle may be easily and quickly lifted, said device embodying a swinging element adapted to accommodate itself to the changes in position of the axle on the raising thereof.

Further objects and advantages of the invention will appear in the course of the subjoined description, and the novelty will be defined by the annexed claim.

Reference is to be had to the accompanying drawings, forming a part of this specification, in which similar characters of reference indicate corresponding parts in all the figures.

Figure 1 is a perspective view illustrating my improved lifting-jack in an operative position with relation to a vehicle-axle, a portion of the vehicle being indicated by dotted lines. Fig. 2 is a fragmentary detail perspective view, and Fig. 3 is a fragmentary detail sectional view. Fig. 4 is a detail view of another form of the hanger.

My improved lifting-jack consists of two members A B and a swinging hanger or suspension-bar C. The members A B are of unequal length, and they are made of wooden bars of proper size. The bar A is provided at one end with a handle or grip portion a, and the two bars A B are disposed inlapping engagement at a point just below the handle a, thus bringing the bars into co-operative positions and permitting them to be connected pivotally together by a through-bolt b, the latter being furnished with a head b' at one end and a nut b² at the other end.

The hanger or suspension-bar C forms one of the important features of my invention because it is loosely suspended from the bolt b and is self-adjusting to changes in position

of the stand or prop afforded by the members A B. The hanger consists of a flat metallic bar which is bent or twisted at a point intermediate of its length, as at c, and the lower end of this hanger is again bent or curved into an offstanding foot-piece C'. The upper end of the hanger C is interposed between the members A B at the crossing-point thereof, and this hanger C is provided with an eye 60 which is arranged to loosely receive the pivotal bolt b, whereby the hanger is operatively connected with the members of the stand, and it is free to turn on the bolt in a way to adjust itself to changes in position of the 65 axle during the operation of lifting and lowering the same. The upper end of the hanger may be spaced relatively to the bars or members by means of washers c², as shown by Fig. 3, which insures the free movement of said 70 hanger.

Instead of making the hanger of flat metal and twisting the same, as shown by Figs. 1 and 2, said hanger may be made of round or curved metal, which allows the lower end 75 thereof to be bent or formed into the foot-piece without twisting the metal, as shown by Fig. 4.

In using my improved lifting-jack the wooden bars are placed astride of an axle at 80 the proper height. The freely-moving hanger falls against the axle and quickly adjusts itself to any height of the axle when it is lifted, so that when the handle a of the long bar A is pulled backward or forward, according 85 to the position in which it is placed, the hook of the hanger is brought upwardly against the axle and lifts the wheel clear of the ground, after which a movement of the hand or foot of the operator presses the short bar 90 B into engagement with the ground and firmly secures the jack in position. When the axle is thus suspended, it is so securely held by the jack that a chance lateral movement of the vehicle or a forward or backward movement of ten or twelve inches may be made 95 without loosening or dropping the axle, because the swinging hanger adjusts itself to the position of the axle, and, in fact, said hanger prevents the vehicle from moving down a 100 slight incline, such as a slanting washing-floor. The bars of the jack are of sufficient

height to permit the device to be easily adjusted to an axle without stooping or requiring the operator to pass between the wheel and the body or the shafts of the vehicle.

5 Having thus described my invention, I claim as new and desire to secure by Letters Patent—

A lifting-jack consisting of members pivoted by a through-bolt one of said members
10 having a handle, and a freely-swinging hanger

loosely suspended from the bolt and provided with an axle-engaging foot-piece.

In testimony whereof I have signed my name to this specification in the presence of two subscribing witnesses.

MELVILLE M. MOORE, SR.
